UNITED STATES PATENT OFFICE.

WILLIAM E. GIBBS, OF FANWOOD, NEW JERSEY, ASSIGNOR OF ONE-HALF TO HENRY BERG, OF NEWARK, NEW JERSEY.

HYDROCARBON-BURNER.

SPECIFICATION forming part of Letters Patent No. 752,900, dated February 23, 1904.

Application filed March 17, 1903. Serial No. 148,170. (No model.)

To all whom it may concern:

Be it known that I, WILLIAM E. GIBBS, a citizen of the United States, residing at Fanwood, in the county of Union and State of New Jersey, have invented certain new and useful Improvements in Hydrocarbon - Burners, of which the following is a specification.

My invention relates to improvements in burners for the heavy oils and hydrocarbons. The object of my invention is to burn oils in such a manner as to convert into useful work the maximum amount of heat units existing therein and to accomplish this end by means of simple and durable devices. In the economical combustion of the heavy oils it is necessary to reduce them to a state of minute subdivision, or, in other words, to convert the oil into the form of a spray or vapor. It is further necessary to mix therewith the requisite volume of air for combustion. Heretofore the subdivision of the oil has been accomplished in one of two ways. Either the oil has been vaporized by heat in a retort under pressure and ejected therefrom in such manner as to induce a flow of air for its combustion or it has been projected as a spray by means of a steam or compressed-air jet, which also induced an air-current for supplying the necessary oxygen. With the light distillates, such as gasolene or benzin, the first method answers well; but when heavy oils are used the retort soon becomes clogged with a deposit of carbon and fails to work. The alternative method requires the use of an air-compressor, since a steam-jet is found to cool the flame, and generally a blower to carry the combustible mixture to the point of ignition in a thoroughly mingled condition. Many burners have been devised in which the mixture of air and spray (or vapor) impinged upon curved metal pieces with the object of obtaining a whirling flame. It has also been proposed heretofore to obtain a more perfect intermingling of the spray or vapor and air by causing a whirling current of air to take up the spray or vapor, the currents being whirled in opposite directions. Such devices are not adapted to produce a whirling flame.

The construction of my burner is shown by the accompanying drawings, in which—

Figure 1 shows one form of my burner in vertical section. Fig. 2 is a plan thereof. Fig. 3 is a vertical sectional view of a modified form of the device.

In the form of burner shown in Figs. 1 and 2, A is a metal cylinder open at both ends and having a plate or partition D near its top pierced by a centrally-located hole B. Depending from plate D and kept at a proper distance by lugs E E is a circular box F, containing a steam-turbine G and having a steam-supply H, jet J so inclined to the radius of turbine G as to cause said turbine G to rotate when steam is blown from the jet J, and exhaust-pipe K. The representation of jet J is diagrammatic and does not show the turn therein. The shaft l of the turbine g is extended upwardly through the hole B and carries upon it a disk M. Said disk has upon its lower face radial ridges or vanes N, which act as fan-blades when the disk is revolved by the turbine G and draw air from the bottom of the cylinder A past the turbine-box F, through the hole B, and throw it out in the form of a strong blast from the top of the cylinder at C C. Oil is fed through the pipe O by way of the hollow upper end of the shaft L to the center of the plate M, from which it is violently projected as a fine spray into the issuing current of air. Any particles of oil which succeed in crossing the gap between the disk M and the cylinder A strike with such force against the wall of said cylinder near the point C that they are still further broken up and rebound into the air-blast. When the burner is in operation, the walls of the cylinder at C become so hot that any excess of oil is vaporized immediately upon reaching them.

The operation of the burner is as follows: Steam is turned into the pipe H, whereby the turbine and fan are put in rapid rotation. A burning torch or other igniting device is placed near the burner and the oil turned into the pipe O. Almost immediately the spray is thrown out from disk M and takes fire from the torch. The rotation of the disk causes the

flame to whirl violently, thereby thoroughly mixing the burning vapors with the air necessary for combustion. A large white flame, burning without smoke, results from this thorough mingling. Moreover, the air which surrounds the outside of the cylinder is drawn up with the whirling flame and adds to its intensity.

In using this burner in furnaces or under boilers it is preferable to surround the burner with a wall of fire-brick, which soon becomes incandescent and serves to relight the burner when for any cause the flame is temporarily extinguished. It is also desirable to carry the exhaust-steam from the turbine into the smoke-stack, where it increases the draft of the chimney.

It will be seen by Fig. 1 that the oil is fed to the disk by way of the hollow upper part of the turbine-shaft, whereby the upper bearing of said shaft is lubricated by the oil on its way to the disk M. Said upper bearing V becomes very hot when the burner is in use, which necessitates a constant flow of oil over it. The lower turbine-bearing is lubricated from an oil-cup (not shown) which supplies the pipe X.

The oil is fed through pipe O either by a pump or by slightly elevating the oil-supply. In Fig. 3, however, I have illustrated a form 30 of the device adapted to itself cause the flow of the hydrocarbon. In this the supply-pipe O' instead of discharging on the upper surface of the disk M discharges into radial passages or tubes M', which when the shaft L is 35 spun by the turbine G discharge the hydrocarbon centrifugally in the annular air-passage between the disk M and edge C, so acting as a pump to draw hydrocarbon from the chamber Z. Here the air-inlet instead of being at the bottom of cylinder A' is in the form 40 of a pipe or passage I of large diameter. In both forms of the invention shown the disk M prevents the direct upward rush of air and confines it to the annular space between the 45 disk and the edge C of cylinder A', resulting under the action of the fan-vanes N in a whirling conical flame disposed over the disk.

I am aware that it has been proposed to utilize an air-blast on its way to the burner to 50 spin oil-distributing surfaces located in the air-passage, thus bringing the oil film in contact

with the air repeatedly and by frictional action causing a certain amount of rotary action of the air; but the arrangement was such as to cause no centrifugal action of the air or oil, the speed of rotation being insufficient unless the air was supplied in such quantities and under such pressure as to prevent the maintenance of combustion. Furthermore, the air-currents in such device were so directed as to oppose each other at the point of exit from the burner, an arrangement not adapted to the production of the whirling flame, which it is my object to obtain.

Having thus described my invention, what I 65 claim as new therein, and desire to secure by Letters Patent, is—

1. In a hydrocarbon-burner, the combination of a casing, a turbine therein, means for admitting an operating fluid to said turbine, 70 a suitable exhaust-outlet for said fluid to a point without the burner, and a revolving fan at the point of combustion and connected with said turbine.

2. In a hydrocarbon-burner, the combination of a turbine with means of supplying fluid for driving same, a centrifugating disk connected therewith for spraying a hydrocarbon, and a fan for producing a whirling motion in the air at the point of combustion, substantially as set forth.

3. In a hydrocarbon-burner, the combination of a turbine with means of supplying fluid for driving same, a centrifugating device for spraying a hydrocarbon, a revolving fan positively driven at a high rate of speed for producing a whirling motion in the air at the point of combustion, and a device for conveying hydrocarbon to said centrifugating device, substantially as set forth.

4. In a hydrocarbon-burner, the combination of a turbine with means of supplying fluid for driving same, a centrifugating disk with means of supplying hydrocarbon thereto, and a revolving fan positively driven at a high velocity for whirling the air in a spiral at the point of combustion, substantially as set forth.

WM. E. GIBBS.
